CLAIM

The ornamental design for an all-terrain vehicle body assembly, as shown and described.

DESCRIPTION

FIG. 1 is a perspective view from the front and left side of the all-terrain vehicle body assembly according to our design;

FIG. 2 is a top plan view thereof;

FIG. 3 is a front elevational view thereof;

FIG. 4 is a rear elevational view thereof; and,

FIG. 5 is a left side elevational view thereof a right side elevational view being a mirror image of the left side elevational view.

Throughout the Figures, the broken lines showing structure form no part of the claimed design.
